UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

UNCOUPLING DEVICE FOR CAR COUPLERS.

Application filed June 4, 1923. Serial No. 643,278.

This particular invention relates to what is generally known in the art as the push down or vertical plane type of uncoupling device and comprises two levers operatively connected having their adjacent ends pivotally mounted on the same fulcrum. Such devices are operated either by hand or foot. (The particular advantage of this construction resides in the manner in which the levers are pivoted upon the fulcrum.) In levers of this general type the connection between the levers must allow the pin lifting lever to move freely laterally to accommodate the longitudinal movement of the coupler in draft and in buffing.

The manner of operatively connecting the two levers and mounting them on a common fulcrum, in accordance with this invention, provides a separate connection allowing play of the fulcrum end of the pin lifting lever in a horizontal plane without transmitting such movement to the operating lever, and furthermore, provides means of operatively attaching the operating lever to the fulcrum which prevents or restricts its lateral movement.

The impact of coupling causes sudden longitudinal movement of the coupler, which movement is transmitted to the adjacent end of the pin lifting lever and would be transmitted to the operating lever unless that lever is prevented from moving laterally.

Switchmen frequently ride a moving car while coupling it and at the same time signal the engineer. In such an act he usually holds on the grab iron with his left hand and signals the engineer with his right hand while his left foot is on the sill step and his right foot is on the operating lever. While in such a position a sudden movement of the operating lever has a tendency to, and frequently does, throw him from the car. One of the objects, therefore, is to provide a device which is safe for the switchman to operate.

A separate connecting member and bearing block has the advantages of increasing the bearing area on the journal fulcrum thereby reducing the friction and making the device easier to operate and also reducing the wear on the associated parts. The connecting block non-rotatively connects the operating lever and the pin lifting lever so

that a force exerted on the outer end of the operating lever raises the inner end of the pin lifting lever.

The connection between the levers surrounds the journal and tilting of the operating lever from the vertical plane is prevented by positioning the operating lever between the pin lifting lever and shoulders on the connecting block and the pin lifting lever is prevented from tilting by being positioned between the operating lever and shoulders on the connecting block. This elimination of the tilting of the levers considerably reduces the friction between the levers and their fulcrum.

Good practice requires that the handle end of the operating lever be positioned slightly in front of the vertical plane of the face of the end sill and below the push pole pocket. This is a generally recognized location of this handle; therefore, switchmen can reach it quickly even in the darkness. It is advantageous, therefore, to not permit the lever to move laterally, and especially advantageous not to allow the sudden or jerky movement of the pin lifting lever to be transmitted to the operating lever.

Another object is to provide an arrangement for connecting the two levers to the fulcrum which also prevents the levers from tipping and thereby binding on the fulcrum and causing friction.

Another object is to form the connector so that the levers can be inserted in the connector only by a movement substantially longitudinally of themselves and to so form the levers that after they are inserted in the connector and the connector mounted upon the journal, that such longitudinal movement is prevented; in other words, the levers are held in place by their relation with the connector and the journal of the fulcrum.

Means are provided to restrict the movement of the lever in a vertical plane which is a requirement of the Interstate Commerce Commission safety appliance acts.

In the drawings:

Fig. 1 is a fragmentary view of a freight car with the device applied thereon.

Fig. 2 is an enlarged detail top plan view of the fulcrum and adjacent ends of the levers with parts broken away.

Fig. 3 is a front elevation of Fig. 2.

Fig. 4 is a section on line 4—4 of Fig. 2.

Fig. 5 is a perspective view of the fulcrum end of the operating lever.

Fig. 6 is a perspective view of the fulcrum end of the pin lifting lever.

Fig. 7 is an enlarged detail plan view of a modification showing the fulcrum and adjacent ends of the lever with parts broken away.

Fig. 8 is a front elevation of Fig. 7.

Fig. 9 is a perspective view of the fulcrum.

Fig. 10 is a perspective view of the connector.

The end sill 1; push pole pocket 2; striking casting 3 and coupler 4 are usual parts of the car. The fulcrum casting 5 is secured to the end sill or other part of the car by rivets 6 and the fulcrum has an integral journal 7 upon which is rotatively mounted the connector 8. This connector is held in operative position by washer 9 which in turn is held in place by bolt 10 and nut 11.

The operating lever 12 is preferably provided with an aperture 13 at its fulcrum end and pin lifting lever 14 is preferably provided with aperture 15 at its fulcrum end. These apertures engage journal 7 of the fulcrum, so as to prevent either lever from moving longitudinally of itself.

The connector 8 may be of a box shape having two vertical walls 16 and 17 which are perforated for engagement with the journal 7 and between which the operating lever 12 and pin lifting lever 14 are mounted on the journal. These vertical walls may be connected at top or bottom or both by horizontal walls 18 and 19. The double bearing of the connector on the journal, as

provided by walls 16 and 17, prevents the connector from tipping from a vertical plane and also increases the bearing area, thereby reducing the friction and making the device easier to operate. The horizontal

wall 18 or 19 causes the operating lever and pin lifting lever to act in unison so that a downward movement on the handle 20 of operating lever 12 causes an upward movement of the inner end 21 of the pin lifting lever thus raising the coupler lock lifter 22.

The vertical walls 16 and 17 are provided with projections 23 and 24 which will be noted in the plan view Fig. 2, are positioned adjacent the center line of the fulcrum. The end of the pin lifting lever 14 is deflected at 25. This arrangement of parts permits the operating and pin lifting levers to move laterally or in a substantially horizontal plane so that the pin lifting lever can accommodate the movements of the coupler in buffing and draft.

The juxta-position of the fulcrum end of the operating lever, the fulcrum end of the pin lifting lever and the projections 23 and 24 prevent the levers from tipping from a

vertical plane. If the levers were permitted to assume an angular position their friction with the journal 7 would be greatly increased. The fulcrum 5 is provided with a lug 26 to limit the rotary movement of the device in a vertical plane.

Figs. 7, 8, 9 and 10 illustrate a modification of the device wherein the lateral movement of the operating lever is prevented or restricted. The lateral movement of the pin lifter lever, caused by the coupler in buffing and draft cannot be transmitted to the operating lever.

In this modification the connector 50 is of a box construction and has vertical walls 51 and 52 and may be connected by horizontal walls 53 or 54 or both. The connector 50 is further provided with vertical walls 55 and 56 which, together with wall 51, form a recess for the insertion of the fulcrum end of the operating lever. This construction prevents (or restricts within commercial limitations) the lateral movement of the operating lever. The walls 52, 55 and 56 are provided with projections 57 and 58 which perform the same functions as projections 23 and 24 heretofore described.

The fulcrum 59 has a journal 60 which engages apertures 61 and 62 of the connector. The lug 63 on the connector engages projections 64 on the fulcrum to limit the rotary movement of the device in a vertical plane.

While I have described the connector as being of box construction, it is understood that either or both of the vertical walls may be used or either or both of the horizontal walls may be used and still come within the scope of this invention.

While this invention is illustrated as applied to a certain type of freight car, it is readily adapted with but slight immaterial changes for application to other types.

I claim:

1. In an uncoupling device for a railway car a fulcrum having a journal, an operating lever mounted directly upon said journal, a pin lifting lever mounted directly upon said journal, and a separate connector for said levers mounted on said journal.

2. In an uncoupling device for a railway car a fulcrum having a journal, an operating lever mounted directly upon said journal, a pin lifting lever mounted directly upon said journal, and a separate connector for said levers mounted on said journal, having means to cause said levers to act in unison in a vertical plane and to permit relative movement of said levers in a horizontal plane.

3. In an uncoupling device for a railway car a fulcrum having a journal, an operating lever mounted directly upon said journal, a pin lifting lever mounted directly upon said journal, and a separate connector for said

levers mounted on said journal having means to cause said levers to act in unison in a vertical plane and to restrict the lateral movement of said operating lever though 5 permitting lateral movement of said pin lifting lever.

4. In an uncoupling device for a railway car a fulcrum having a journal, a separate connector having two walls, each bearing 10 on said journal, an operating lever, and a pin lifting lever, said levers mounted on said journal between said walls.

5. In an uncoupling device for a railway car a fulcrum having a journal, a separate connector having two walls, each bearing on 15 said journal, an operating lever, and a pin lifting lever, said levers mounted on said journal between said walls, said connector having means to restrict the lateral movement 20 of said operating lever and to permit lateral movement of said pin lifting lever.

6. In an uncoupling device for a railway car a fulcrum having a journal, an operating lever mounted directly upon said journal, a pin lifting lever mounted directly upon said journal, and a separate connector for said levers mounted on said journal having means to retain the fulcrum ends of said levers in a substantially vertical plane.

7. In an uncoupling device for railway cars comprising a fulcrum having a journal, a separate connector having two walls each bearing on said journal, an operating lever, and a pin lifting lever, said levers mounted on said journal between said walls, said connector having means to cause said levers to act in unison in a vertical plane and to permit relative movement of said levers in a horizontal plane.

8. In an uncoupling device for railway cars comprising a fulcrum having a journal, a separate connector having two walls each bearing on said journal, an operating lever, and a pin lifting lever, said levers mounted on said journal between said walls, said connector having means to retain the fulcrum ends of said levers in a substantially vertical plane.

9. In an uncoupling device for railway cars comprising a fulcrum having a journal, a separate connector having two walls each bearing on said journal, an operating lever, and a pin lifting lever, said levers mounted on said journal between said walls, said connector having means to retain the fulcrum ends of said levers in a substantially vertical plane, and to permit relative movement of said levers in a horizontal plane.

10. In an uncoupling device for railway cars comprising a fulcrum having a journal, an operating lever, a pin lifting lever mounted directly upon said journal, and a separate connector for said levers mounted on said journal having means to cause said

levers to act in unison in a vertical plane and to restrict the lateral movement of said operating lever though permitting lateral service movement of said pin lifting lever.

11. In an uncoupling device for a railway car coupler, a fulcrum having a journal, an operating lever mounted upon said journal, a pin lifting lever mounted upon said journal, and a connector mounted upon said journal operatively connecting said levers, 70 said levers insertable in said connector only by a movement substantially longitudinally of themselves, said levers so formed that after they are inserted in said connector and the connector is mounted upon the journal, said longitudinal movement is prevented.

12. In an uncoupling device for railway cars a fulcrum having a journal and a lug, an operating lever mounted directly upon 85 said journal, a pin lifting lever mounted directly upon said journal, and a separate connector for said levers mounted on said journal and provided with a stop to engage said lug to restrict the rotative movement of said connector about said fulcrum. 90

13. An uncoupling device comprising in combination a connector, a fulcrum whereon said connector is oscillatably supported and a lever including a handle arm and an operating arm disposed oppositely and having their adjacent ends detachably secured to said connector, said connector being formed to receive and hold the said ends in effective mutual relation, and said arms each being formed to receive said fulcrum transversely whereby they are locked in said connector and secured against appreciable endwise movement. 95

14. An uncoupling device comprising in combination a connector, a fulcrum whereon said connector is oscillatably supported, and a sectional lever having operating and pin lifting arms, said connector being apertured to receive and hold said pin lifting arm co-rotatably therewith and free for limited horizontal oscillation to accommodate coupler movement when in use, said connector coacting with said operating arm when the latter is actuated to lift the pin, and said fulcrum and connector being shouldered to limit the movement of said connector. 100

15. In a release rigging for a car coupler, an operating lever having an aperture adjacent its fulcrum end, a pin lifting lever having an aperture adjacent its fulcrum end, a connector operatively connecting said levers and provided with an aperture, a journal fulcrum passing through all of said apertures, and means to retain the parts in operative relation. 115

16. In a release rigging for a car coupler, an operating lever with a rectangular portion having an aperture adjacent its fulcrum end, a pin lifting lever with a rectangular 120 125 130

- portion having an aperture adjacent its fulcrum end, a connector comprising a vertical wall with an aperture and spaced apart horizontal walls, said levers positioned between said horizontal walls whereby they are operatively connected, a journal fulcrum passing through all of said apertures, and means to retain the parts in operative relation.
- 10 17. In a release rigging for a car coupler, a fulcrum having a journal, an operating lever rotatively mounted directly upon said journal, a pin lifting lever rotatively mounted directly upon said journal, and a connector rotatively mounted upon said journal and provided with means to cause said levers to act in unison in a vertical plane.
- 15 18. In a release rigging for a car coupler, a fulcrum having a journal, an operating lever rotatively mounted directly upon said journal, a pin lifting lever rotatively mounted directly upon said journal, and a connector having a vertical portion rotatively mounted upon said journal and a horizontal portion which causes said levers to act in unison in a vertical plane.
- 20 19. In a release rigging for a car coupler, a fulcrum having a journal, an operating lever perforated to form a journal bearing upon said journal, a pin lifting lever perforated to form a journal bearing upon said journal, and a connector having a vertical portion perforated to form a journal bearing upon said journal and provided with means to cause said levers to act in unison in a vertical plane.
- 25 20. In an uncoupling device for a railway car, a fulcrum having a journal, an operating lever mounted upon said journal, a pin lifting lever, and a connector mounted upon said journal provided with means to cause said levers to act in unison in a vertical plane, said connector comprising oppositely disposed portions spaced apart a distance substantially equal to the width of the pin lifting lever in one vertical plane only, said pin lifting lever mounted upon said journal between said portions whereby a lateral swinging movement of said pin lifting lever is permitted.
- 30 21. In an uncoupling device for a railway car, a fulcrum having a journal, an operating lever, a pin lifting lever, and a connector mounted upon said journal provided with means to cause said levers to act in unison in a vertical plane, said connector comprising oppositely disposed portions spaced apart a distance substantially equal to the width of the pin lifting lever in one vertical plane only, said pin lifting lever mounted upon said journal between said portions whereby a lateral swinging movement of said pin lifting lever is permitted, said connector also comprising parallel walls spaced apart substantially equal to the width of said operating lever, said operating lever mounted upon said journal between said walls whereby any appreciable lateral swinging movement of said operating lever is prevented.
- 35 22. A connector for levers in an uncoupling device for railway cars comprising spaced apart walls with registering perforations, said walls being nearer together adjacent said perforations.
- 40 23. A connector for levers in an uncoupling device for railway cars comprising spaced apart walls with registering perforations, said walls being nearer together adjacent said perforations, and an integral portion positioned between said walls and parallel to one of said walls.
- 45 24. In an uncoupling device for a railway car, a fulcrum having a journal, an operating lever, a pin lifting lever, and a separate connector mounted on said fulcrum operatively connecting said levers, each of said levers formed to receive the journal so that their longitudinal movement is restricted.
- 50 25. In a device of the character described, a leverage arm connector apertured for pivotal mounting and having a pair of substantially parallel apertures on opposite sides of the pivot aperture and intersecting same, one of said parallel apertures being flared in both directions from the point of intersection referred to for accommodating the necessary normal free movement of an operating arm due to car or coupler movement.
- 55 26. An uncoupling device comprising in combination a connector, a fulcrum whereon said connector is oscillatably supported, and a lever having flexibly connected operating and pin lifting arms, said connector being apertured to receive and hold said pin lifting arm co-rotatably therewith and horizontally oscillatable to accommodate tractive movement of the coupling when in use, and said connector being shouldered to coact with said operating arm when the latter is actuated to lift the pin.
- 60 27. An uncoupling device comprising in combination a connector adapted to serve as a fulcrum bracket, a fulcrum whereon said connector is oscillatably supported, and a sectional lever having flexibly connected operating and pin lifting arms, said connector being apertured to receive and hold said pin lifting arm co-rotatably therewith and free for limited horizontal oscillation to accommodate coupler movement when in use, said connector co-acting with said operating arm when the latter is actuated to lift the pin, and said fulcrum and connector being shouldered to limit the movement of said connector.
- 65 28. In an uncoupling device for a car coupler, a fulcrum with a journal, a mem-

ber having an aperture engaging said journal and having another aperture normal thereto, and a lever loosely fitting in said other aperture, said lever provided with means cooperating with said journal restricting the longitudinal movement of said lever.

29. In an uncoupling device for a car coupler, a fulcrum with a journal, a member

having an aperture engaging said journal 10 and having another aperture normal thereto, and a lever loosely fitting in said other aperture, said lever provided with a portion entirely surrounding said journal thereby restricting the longitudinal movement of said 15 lever.

ARTHUR E. SMALL.
